UNITED STATES PATENT OFFICE.

GEORGE P. JAMESON, OF ABINGDON, ILLINOIS.

GRAIN-WEIGHING APPARATUS.

SPECIFICATION forming part of Letters Patent No. 375,163, dated December 20, 1887.

Application filed April 27, 1887. Serial No. 236,316. (No model.)

To all whom it may concern:

Be it known that I, GEORGE P. JAMESON, of Abingdon, in the county of Knox and State of Illinois, have invented a new and Improved 5 Grain Weighing and Measuring Machine, of which the following is a full, clear, and exact description.

The object of my invention is to provide a new and improved grain weighing and measuring machine which is simple and durable in construction and very effective and automatic in operation.

The invention consists in the construction and arrangement of various parts and details 15 and combinations of the same, as will be fully described hereinafter, and then pointed out in the claims.

Reference is to be had to the accompanying drawings, forming a part of this specification, 20 in which similar letters of reference indicate corresponding parts in all the figures.

Figure 1 is a side elevation of my improvement attached to a thrashing-machine. Fig. 2 is an enlarged side elevation of my improvement, and Fig. 3 is an end elevation of part of 25 the same.

My improvement is specially adapted for thrashing-machines which convey the thrashed grain into a machine which, after automatically weighing and measuring the grain, delivers it to a wagon or other receptacle.

My improvement A is supported on an L-shaped arm, B, secured by the end of its vertical arm to the top of the thrashing-machine 35 C in such a manner that my improvement hangs over the side of the thrashing-machine C and can be swung sidewise. On the outer end of the arm B is hung a spring weighing-scale, D, of any suitable construction, and connected at its lower end with a U-shaped arm, E, in which is mounted to turn the shaft F, carrying the grain-weighing cylinder G, which consists of the two circular end plates, G', connected with each other by four radial partitions, G², extending at right angles to each other, so as to form four equal compartments in the grain-measuring cylinder G. The weight of the latter and of the U-shaped arm E is supported by a lever, H, engaging with its front 40 end said U-shaped arm E, being fulcrumed on

a U-shaped brace, I, secured to the braces I' and I², fastened to the arm B.

On the inner end of the lever H is mounted adjustably the balance-weight H', which can be accurately set on said lever H to balance 55 the grain-measuring cylinder G and its U-shaped arm E.

On the outside of the sides G' of the grain-measuring cylinder G are secured the four lugs G³, held near the rims of said sides G' and midway between the outer ends of the partitions G². The lugs G³ are alternately engaged by a hook, J', formed on the outer end of the lever J, fulcrumed on the brace I', and connected at its inner end with one end of a 60 spring, K, secured by its other end to the U-shaped brace I. The position of the lever J can be regulated by a screw, L', engaging the top edge of said lever J and screwing in a U-shaped keeper, L, pivoted to the brace I², the 65 lever J passing through said keeper.

The lugs G³ are also alternately engaged on their other side by a hook, N', formed on the outer end of the arm N, pivoted on the lever J between its fulcrum on the brace I' and its hook J'. On the under edge of the arm N, 75 near its fulcrum, is formed a transverse lug, N², adapted to engage the lower edge of the lever J, whereby said arm N is held in a horizontal position in line with said lever J.

The grain-weighing cylinder G is prevented from moving sidewise and endwise by the links O, pivotally connected with the shaft F and with the lower ends of the braces I². Into the compartments formed by the partitions G² in 85 the weighing and measuring cylinder G opens the lower end of the chute P, held in an upwardly-inclined position and supported at its upper end by the link Q and the L-shaped arm B, which is provided with a pin, B', to prevent the link Q from slipping. Into the chute P opens a flexible chute, C, connected with the upper end of the grain-elevator C², into the lower end of which discharges the spout C', 90 extending from the grain-box of the thrashing-machine C.

The operation is as follows: The grain-weighing cylinder G stands in its normal position, as shown in Figs. 2 and 3, in which the partitions G² extend at an angle of forty-five de- 95 100

grees to the horizontal plane. The chute P opens into the top compartment and the grain delivered from the thrashing-machine by the elevator C² to the chute C³ passes into the chute 5 P and fills the upper compartment. The grain-measuring cylinder G is held in this position by the hooks J' and N' engaging the respective lugs G³ on the sides G', of the cylinder G until the weight of the grain in the compartment moves the parts of the spring-scale D so far apart that the grain-cylinder G is lowered until the hooks J' and N' disengage the respective lugs G³. The weight of the grain in the uppermost compartment then causes the 10 cylinder G to rotate, whereby the grain in said compartment is emptied into the wagon or other receptacle standing below the grain-weighing cylinder. As soon as the grain begins to empty out of the cylinder G then the 15 parts of the spring-scale D move again to their former positions, whereby the grain-cylinder G is raised to its normal position, and, as the cylinder at the same time rotates, then the next following lug G³ is engaged by the hooks 20 J' and N' of the lever J and the arm N, respectively. The lugs G³ of the grain-weighing cylinder G are disengaged from the hooks J' and N' as soon as the weight of the grain has moved the cylinder downward sufficiently so 25 that the upper edge of the lug G³ is below the lower ends of the hooks J' and N', and as the height of the latter can be regulated by the screw L' it is evident that the grain in the respective compartments can be discharged 30 when any desired weight is obtained. When the grain-weighing cylinder G turns in the direction of the arrow a', as before described, then the respective lug G³ in its upward movement strikes against the under side of the arm N, thus lifting the same until the lug G³ strikes 35 against the hook J', after which the arm N drops downward again, so that its hook N' engages the other side of the lug G³, and the lug N² of the arm N, striking against the under 40 edge of the lever J, prevents the further downward motion of said arm N. As the arm B can be swung sidewise, it permits of moving the grain weighing or measuring machine over a second wagon in case the first one is filled 45 without interrupting the passage of the grain from the elevator C² into the chute P.

The arm B may be mounted on top of the thrashing-machine or on the side or front of the same, or on a separate stand.

50 The machine may also be used for weighing coal or other substances, and employed not only in thrashing-machines, but also in stores, warehouses, &c.

In regard to the use of both spring-scale and 55 scale-beam, or balance-weight, as it is used here, the object is to accurately measure the grain, and this can only be done by weight, as grain varies so much in weight, by measure. Some grain falls short in weight, while other 60 grain overruns in weight by the measure. Now, to simply measure the grain the spring - scale

or scale-beam, either one, would be sufficient; but to measure the grain accurately it must be weighed, and the simplest means of weighing it is by spring-scales. If spring - scales alone 70 are used, the weight of the measure comes on the scales and you have the weight of the measure on scales over and above the weight of the grain, whereas in using the scale-beam (or balance-weight) the weight of measure is 75 taken from the scales, so the scales support and show only the weight of the grain. In using the scale-beam (or balance-weight) in connection with scales I may always (by moving the weight back or forward, as the case may 80 be) have the scales evenly balanced. In this way the scales are in no strain except in weighing the grain and showing to the ounce how much grain is in measure. I find by actual test the apparatus operates much more accurately and with much more satisfaction with 85 both spring-scale and scale-beam.

Having thus fully described my invention, I claim as new and desire to secure by Letters Patent—

1. In a grain weighing and measuring machine, the combination, with a spring weighing-scale, of a counterbalanced grain-cylinder connected with said scale, lugs formed on the sides of said cylinder, hooks engaging said lugs, and adjustable lever-arms carrying said hooks, so that when the uppermost compartment of the grain-cylinder is filled with a certain amount of grain then the lugs are disengaged from said hooks, substantially as shown 90 and described.

2. In a grain weighing and measuring machine, the combination, with a spring-scale, of a counterbalanced grain-cylinder connected with said scale and provided with four compartments formed by partitions secured to the sides of said cylinder, substantially as shown 95 and described.

3. In a grain weighing and measuring machine, the combination, with a spring-scale, of 100 a U-shaped frame connected with said scale, a grain-cylinder mounted in said U-shaped frame and provided with compartments formed by partitions secured to the sides of said cylinder, and links connected with the shaft of said cylinder, so as to prevent it from moving sidewise and endwise, substantially as shown and 105 described.

4. In a grain weighing and measuring machine, the combination, with a spring-scale, of 110 a counterbalanced grain-cylinder connected with said scale and provided with compartments formed by partitions secured to the sides of said cylinder, and means, as described, for holding said cylinder in a locked position 115 until its uppermost compartment is filled with a certain amount of grain, as set forth.

5. In a grain weighing and measuring machine, the combination, with a spring-scale, of 120 a counterbalanced grain - cylinder connected with said scale and provided with compartments formed by partitions secured to the 125

sides of the cylinder, lugs formed on the outside of the sides of the cylinder midway between said partitions, and hooks engaging the uppermost lugs on said cylinder until the uppermost compartment of the cylinder is filled 5 with a certain amount of grain, substantially as shown and described.

6. In a grain weighing and measuring machine, the combination, with a spring-scale, of a counterbalanced grain - cylinder connected with said scale and provided with compartments formed by partitions secured to the sides of the cylinder, lugs formed on the sides of said cylinder midway between the partitions, a hook engaging one side of the uppermost lug on said cylinder, an adjustable lever carrying said hook, and an arm pivoted on said lever and provided with a hook engaging the other side of said uppermost lug, substantially as shown and described. 15
20

7. In a grain weighing and measuring machine, the combination, with a spring-scale, of a counterbalanced grain - cylinder connected with said scale and provided with compartments formed by partitions secured to the sides of the cylinder, lugs formed on the sides of said cylinder midway between the partitions, a hook engaging one side of the uppermost lug on said cylinder, an adjustable lever carrying said hook, an arm pivoted on said lever and provided with a hook engaging the other side of said uppermost lug, and means, substantially as described, for regulating the position of the hooks in relation to said lugs, as set forth. 25
